UNITED STATES PATENT OFFICE.

JOHN R. FORTUNE, OF DETROIT, MICHIGAN.

STOKER-BOX DRIVE.

1,149,435.

Specification of Letters Patent. Patented Aug. 10, 1915.

Application filed January 16, 1914. Serial No. 812,591.

To all whom it may concern:

Be it known that I, JOHN R. FORTUNE, a citizen of the United States of America, residing at Detroit, in the county of Wayne and State of Michigan, have invented certain new and useful Improvements in Stoker-Box Drives, of which the following is a specification, reference being had thereto in the accompanying drawings.

10 In the operation of automatic stokers of the type in which the fuel is fed onto the upper ends of inclined grate bars, said grate extending from the front to the rear of the furnace, it is found that when the fuel is fed in equal amounts throughout the length 15 of the grate the most efficient operation of the furnace is not secured owing to the unequal burning of the coal on the grate, the fuel upon the rear portion thereof being 20 most quickly consumed.

It is an object of this invention to provide a simple and efficient means whereby the feeding of the fuel to certain portions of the grate may be varied independently of the 25 means for supplying fuel to other portions thereof and further, to provide a simple construction of stoker box actuating means whereby the parts may be easily detached for the purpose of replacement or repair.

30 It is also an object of the invention to provide certain other new and useful features in the construction and arrangement of feeding mechanisms, all as hereinafter more fully described.

35 To these ends the invention consists in the matters hereinafter more fully set forth and pointed out in the appended claims, reference being had to the accompanying drawings in which:—

40 Figure 1 is a transverse vertical section through a furnace provided with automatic stokers having feeding mechanism embodying the invention. Fig. 2 is a detail showing a longitudinal section through a series 45 of stoker boxes embodying the invention, portions being broken away to shorten the figure; Fig. 3 is an enlarged transverse vertical section through one of the stoker boxes and adjacent parts; Fig. 4 is a perspective view of a portion of one of the 50 boxes detached; and Fig. 5 is a perspective view of a filler block.

55 For convenience of illustration, the invention is shown as applied to what is known as a "Murphy" type of furnace in which there are two opposite sets of grate bars 1

supported at their lower ends upon a grate bearer 2 with their upper ends adjacent to the inner edges of coking plates 3 extending along each side of the furnace from 60 front to rear thereof below the lower ends of magazines 4, the inner side of each of which is formed by an arch plate 5 and the lower side of the discharge throat or inclined bottom of each of which is formed 65 by a detachable plate 6 beneath the lower edge of which bottom a series of stoker boxes 7 is reciprocated upon the coking plate to push fuel falling from the magazine upon said plate, from the same onto the upper 70 ends of the inclined grate bars. It will, however, be understood that this invention may be applied to other types or constructions of automatic stokers where reciprocable pushers or stoker boxes are employed 75 to feed fuel onto the grates.

The several stoker boxes 7 have the general external form common to devices for this purpose in stokers of this type and each is reciprocated upon the coking plate 80 by means of urgents or arms 8 upon a shaft 9 extending longitudinally beneath each series of boxes. Each arm is formed with a sleeve portion in the form of a split ring 10 to embrace the shaft and is secured in 85 place thereon by providing the shaft with a short key 11 whenever it is desirable to secure an arm to the shaft, said key engaging a notch in the sleeve which is drawn into clamping engagement with the shaft by 90 bolts 12 passing through out-turned ends or ears 13 on the split ring. The outer ends of the arms 8 are enlarged forming a head 14 on each arm having rounded edge contact surfaces to engage the contact sides 15 of 95 an opening 16 in a block 17 which is detachably held within each stoker box by providing horizontally disposed longitudinally extending ribs or ledges 18 upon opposed walls of the box and forming the block with 100 shoulders 19 to engage the upper sides of the ledges by forming a groove 20 along each lower side angle of the block. Two of the arms or urgents 8 are preferably provided for each box, one near each end, and at the 105 outer ends of the ledges 18 for supporting each block for each urgent, is a transverse wall 21 forming a stop or abutment for the block which is engaged with the ledges by placing the block in the box intermediate its 110 ends and then moving it longitudinally thereof over the inner ends of the ledges.

When the boxes are in place with the heads 14 of the urgents engaged with the blocks and the urgents secured in their proper positions on the shaft, the blocks are held by 5 the urgents against longitudinal movement in the boxes and disengagement from the ledges.

As shown in Fig. 3 the hole 16 in each block may be of greater width than the 10 width of the head 14 of the arm and there will, therefore, be lost motion between the arm and box in turning said shaft to actuate the boxes. If it is desirable to feed the maximum amount of fuel, blocks are inserted 15 having openings just large enough to receive the heads of the urgents, but if a lesser amount is required, blocks having large holes are used, thus decreasing the feeding movement of the box due to the lost 20 motion or idle movement of the arm. With a fixed length of movement of the urgents, the feeding movement of the boxes may therefore be varied to suit conditions of installation by placing blocks which will give 25 the desired movement.

When it is found desirable to feed less fuel to one part of the grates than to other parts, the boxes at the forward end of each series may be actuated independently of 30 those at the rear end by providing a sleeve 22 on the forward end of each shaft 9 to which sleeve the urgents for the forward boxes are secured in the same manner that the other urgents are secured to the shaft. 35 Any suitable means (not shown) may be attached to the angularly formed forward end of each sleeve outside of the furnace front for turning the sleeve to reciprocate the forward boxes and similar means may be provided 40 on the squared forward end of each shaft which projects through the sleeve, for turning the shaft to actuate the rear boxes. The shafts and their sleeves may be turned in timed relation to each other by any suitable 45 means (not shown) in the usual manner of automatically operating stoker boxes. A greater amount of fuel may therefore be fed to the rear portion of each grate than to its forward portion and the feed thus regulated 50 to keep every part of the grate covered, thus giving the most efficient operation and preventing the burning out of the grate bars.

Stokers of this construction are cheap to 55 manufacture and may be quickly and easily installed or repaired but it is obvious that changes may be made therein without departing from the spirit of the invention and I do not, therefore, limit myself to the form 60 or arrangement shown.

Having thus fully described my invention, what I claim is:—

1. In an automatic stoker, the combination of a plurality of members for feeding fuel, a shaft extending longitudinally of 65

said members, means on said shaft for actuating certain of said members, an actuating member extending longitudinally of said shaft, and means on said actuating member for actuating the other of said members. 70

2. In an automatic stoker, the combination of a series of separate members for feeding fuel, a shaft extending longitudinally of said series, a sleeve on said shaft, means on said sleeve for operating certain of 75 said members, and means on the shaft for operating the other of said members.

3. In an automatic stoker, the combination with a coking plate, a grate adjacent to said plate, and a magazine above the plate, 80 of a series of stoker boxes slidable upon said plate beneath the magazine for feeding fuel therefrom, a shaft mounted in bearings beneath the coking plate and extending longitudinally thereof, a sleeve on the forward 85 end of said shaft of lesser length than the shaft and operable independently thereof, a series of members on the shaft for operating certain of said stoker boxes, and a series of members on the sleeve for operating the 90 other of said boxes.

4. In an automatic stoker, the combination with a coking plate, a grate adjacent to said plate and a magazine above the plate, 95 of a series of stoker boxes slidable upon said plate beneath the magazine for feeding fuel therefrom, a shaft mounted in bearings beneath the coking plate and extending longitudinally thereof, a sleeve on the forward 100 end of said shaft of lesser length than the shaft, a series of arms detachably secured to said shaft beyond the end of said sleeve and extending upward into engagement with certain of said boxes, and a series of arms detachably secured to said sleeve and 105 extending upward into engagement with the other of said boxes, the outer end of said shaft and sleeve being adapted for the application thereto of power for turning the same to reciprocate the boxes. 110

5. In an automatic stoker, the combination with a reciprocable member for feeding fuel, of a detachable block carried by said member and provided with an opening, and a movable arm having an end of lesser 115 width than the width of the opening to engage said opening and actuate said member, whereby said member will be reciprocated a lesser distance than the length of movement of the arm and the distance of reciprocation 120 may be changed by detaching the block and substituting another having a different sized opening.

6. In an automatic stoker, the combination of a plurality of reciprocable members 125 for feeding fuel, blocks detachably secured within said members and having openings in their lower sides of different widths and a series of upwardly extending actuating arms having upper ends within said open- 130

ings of lesser width than the width of said openings, said arms being adapted to turn upon a horizontal axis extending longitudinally beneath said members, and said blocks 5 being interchangeable.

7. In an automatic stoker, the combination with a coking plate, of a stoker box reciprocable across said plate, a block detachably secured within said box and having an 10 opening in its lower side, a shaft extending longitudinally beneath said plate, and an upwardly extending arm on said shaft with its upper end projecting into the opening in the block to reciprocate the box upon the 15 turning of the shaft, the opening in the block being of greater width than the effective width of the arm to provide a lost motion between the arm and box for the purpose described.

8. In an automatic stoker, the combination of a reciprocable member for feeding fuel formed to receive a block, a removable block 20 engaged with or disengaged from said member by a sliding movement of the block and 25 provided with an opening, a shaft, and an arm adjustably secured upon said shaft and loosely engaging said opening and holding the block against disengagement from said member.

9. In an automatic stoker, the combination of a reciprocable member for feeding fuel formed with a seat to receive and detachably hold a block, a block detachably engaged with said seat, a shaft, and an arm 30 secured upon the shaft in engagement with said block to reciprocate said member and to hold the block in its seat thereon.

10. In an automatic stoker, the combination of a series of stoker boxes for feeding fuel each provided with longitudinally extending parallel ledges, blocks to engage and rest upon said ledges and each formed with an opening in its lower side, a shaft supported longitudinally beneath said series of boxes, and arms detachably secured to 40 said shaft and provided with enlarged heads at their upper ends to engage the openings in said blocks.

11. In an automatic stoker, the combination with a coking plate extending from 50 front to rear of a furnace, a grate with its edge adjacent to the edge of said plate, and a magazine above the plate, of a series of separately movable stoker boxes reciprocable over said plate beneath said magazine, each 55 box being formed with transverse walls and opposed parallel ledges on opposite longitudinal walls extending from the transverse walls, blocks formed with shoulders to rest upon said ledges within the boxes and each 60 having an opening extending vertically therethrough, bearings beneath the coking plate, a shaft in said bearings, a sleeve on the shaft of lesser length than the shaft, and a series of arms detachably secured to said 65 shaft and sleeve with their upper ends within the openings in the blocks.

In testimony whereof I affix my signature in presence of two witnesses.

JOHN R. FORTUNE.
